UNITED STATES PATENT OFFICE.

NIXON LEE, OF BROOKLYN, NEW YORK, ASSIGNOR, BY MESNE ASSIGNMENTS, TO NATIONAL SEAL COMPANY, INC., OF BROOKLYN, NEW YORK, A CORPORATION OF NEW YORK.

LATCH.

1,346,129.

Specification of Letters Patent. Patented July 13, 1920.

Application filed May 10, 1919. Serial No. 296,048.

To all whom it may concern:

Be it known that I, NIXON LEE, a citizen of the United States, and a resident of the borough of Brooklyn, in the county of 5 Kings and State of New York, have invented certain new and useful Improvements in Latches, of which the following is a specification, reference being made to the accompanying drawings, forming a part 10 thereof.

My invention relates to latches used particularly in doors for motor-cars or other road vehicles, and the objects of my invention are, among other things, to provide an 15 improved latch of this type which, when the door is closed, will adapt itself readily to the elasticity of the motor car body, and in which the several movable elements of the latch are held yieldingly under spring 20 pressure so as to avoid any looseness or rattling of the door as well as of the component parts of the latch itself. A further 25 object of my invention is to simplify and cheapen the construction of latches of this type without loss of efficiency in operation, or in their coaction with the striker plate of the car body when the door is closed.

Further advantages and functions of my improved latch will hereinafter be more particularly set forth, and a preferred embodiment of my invention is illustrated in the accompanying drawings in which—

Figure 1 is an interior elevation of my improved latch;

Fig. 2 is a vertical sectional view taken on the line 2—2 of Fig. 1 looking in the direction of the arrow;

Fig. 3 is a horizontal sectional view taken on the line 3—3 shown in Fig. 1;

Fig. 4 is a horizontal sectional view taken on the line 4—4 shown in Fig. 1;

Fig. 5 is a top plan view; and

Fig. 6 is a perspective view showing the shape and configuration of a preferred form 45 of a sliding actuating plate member.

Similar numerals refer to similar parts throughout the several figures.

Referring to the drawings the latch casing 7 has one end bent at a suitable angle 50 to form the face 8 and to provide with the frame 9 secured to the casing 7 a suitable incasement to support and hold the various parts of the latch or lock in position. The face 8 has formed therein a guide opening

10 for a bolt-head passage from within the 55 incasement; the latching-bolt 11 provided with the customary beveled head 12 projects normally through the guide opening 10 to engage with the striker plate (not shown) of the car body through the tension 60 of the coil spring 13, the inner end of which spring bears against the inner end of the frame 9 and the other end bears within the recess 14 formed in the inner end of the bolt 11, as shown in Figs. 1 and 4. Above the 65 latching-bolt 11 is arranged the sliding plate member 15 shown in perspective in Fig. 6; this plate 15 has the integrally formed lugs 16 projecting laterally through the two slots 17 formed in the frame 9 which 70 serve to preserve the vertical alinement of the plate within the incasement. The plate member 15 has also the integral depending lug 18 projecting downwardly to coact with the bolt 11 within the cutaway portion 19 75 formed therein as shown in Figs. 1 and 4. The spring 20 having the pins 21 and 22 contained within its coils to hold the spring in lateral alinement bears against the lug 18 and the frame 9 as shown in Fig. 1, and 80 normally holds the plate 15 in its extreme forward position toward the left.

The vertical hand-lever 23 to retract the latching-bolt 11 within the incasement is mounted on the shaft 24 suitably journaled 85 in the casing 7 as shown in Fig. 3, and this shaft 24 carries within the incasement the vertically swinging arm 25 which is adapted to coact with, and press inwardly, the projecting shoulder 26 integrally formed 90 with the plate member 15. When the plate member 15 is in its outermost position as shown in Fig. 1, the arm 25 is held firmly against the lug 27 by the stress of the spring 20 acting through the shoulder 26. 95 The latching-bolt 11 may also be retracted by suitable knobs or keys (not shown) secured to the shaft 28 which carries the vertically swinging arm 29 adapted to coact with, and press inwardly, the projecting shoulder 30 integrally formed in the plate member 15. When the plate member 15 is in its left hand position shown in Fig. 1, the arm 29 is pressed forwardly against the inner surface of the face 8 by the stress of 105 the coil spring 20 acting through the shoulder 30. The operation of my latch is plain, and from the foregoing arrangement of

the movable parts of my latch it is also apparent that when the door is closed and the latching-bolt 11 projected within the recess of the striker plate by the spring 13, 5 the sliding plate 15 presses yieldingly through the spring 20 toward the left, and, by its shoulders 26 and 30 bearing against the swinging arms 25 and 29 respectively holds the latter snugly under spring pressure 10 against the lug 27 and inner surface of the face 8 respectively. These arms 25 and 29, being so held under spring pressure, serve to hold the shaft 24 and hand lever 23 as well as the shaft 28 with the actuating knobs or keys against undesirable 15 looseness and rattling. By this improved construction it is obvious that all the actuating elements of my latch are yieldingly held under spring pressure when the bolt head 12 is projected through the guide opening 10, and that either the hand lever 23 or the knobs acting on the shaft 28 may be used interchangeably in retracting the bolt 11 and plate 15 against spring pressure. 20

It should also be noted that the latching bolt 11 may be retracted against the tension of the spring 13 by its beveled head 12 coacting with the striker plate without moving laterally the sliding-plate 15, the depending lug 18 moving to the left through the cutaway portion 19, or the bolt 11 may be retracted in the ordinary manner either by the hand lever 23 or by the knobs or 30 keys rotating the shaft 28 by having the lug 18 press against the inner face of the cutaway portion 19 of the bolt in which case all the movable parts would be supported and held in their respective operative 35 positions under the yielding pressure of both springs 13 and 20.

It will be understood that the latch herein shown and described is a preferred embodiment of my invention and that the same may be modified and changed in its various details without departing from the principle and scope of my invention and without sacrificing any of its advantages. 45

I claim as my invention:—

50 1. A latch comprising a latching-bolt, a spring constantly forcing said bolt into its extended position, a unitary laterally sliding member bearing against said bolt only to retract same, a second spring connected with 55 said unitary member to hold the latter under outward spring pressure in all positions of said latching-bolt, and means, comprising a pair of independently operable swinging arms, each yieldingly held in inoperative position by 60 said second spring, to actuate said sliding member against both of said springs to retract said bolt.

65 2. A latch comprising a latching-bolt, a spring constantly forcing said bolt into its extended position, a unitary laterally slid-

ing member bearing against said bolt only to retract same, a second spring connected with said unitary member to hold the latter under outward spring pressure in all positions of 70 said latching-bolt and means, comprising a pair of independently operable vertically swinging arms each yieldingly held in inoperative position by said second spring, to actuate said sliding member against both of said springs to retract said bolt. 75

3. A latch comprising a latching-bolt, a spring constantly forcing said bolt into its extended position, a unitary laterally sliding member bearing against said bolt only to retract same, a second spring connected with 80 said unitary member to hold the latter under outward spring pressure in all positions of said latching-bolt, and means, comprising a pair of spaced-apart, independently operable, vertically swinging arms each yieldingly held in inoperative position by said second spring, to actuate said sliding member against both of said springs to retract said bolt. 85

4. A latch comprising a latching-bolt, a 90 spring constantly forcing said bolt into its extended position, a unitary laterally sliding member bearing against said bolt only to retract same, a second spring connected with 95 said unitary member to hold the latter under outward spring pressure in all positions of said latching-bolt means, comprising a pair of independently operable swinging arms, to actuate said sliding member against both of said springs to retract said bolt, and stops 100 held by said second spring when in their retracted position.

5. A latch comprising a latching-bolt, a spring constantly forcing said bolt into its 105 extended position, a unitary laterally sliding member bearing against said bolt only to retract same, a second spring connected with said unitary member to hold the latter under outward spring pressure in all positions 110 of said latching-bolt, both springs being arranged in mutual parallelism within the latch, and means, comprising a pair of independently operable swinging arms, each 115 yieldingly held in inoperative position by said second spring, to separably actuate said sliding member against both of said springs to retract said bolt. 120

6. A latch comprising a latching-bolt, a spring constantly forcing said bolt into its 120 extended position, a unitary laterally sliding member bearing against said bolt only to retract same, a second spring connected with said unitary member to hold the latter under outward spring pressure in all positions of 125 said latching-bolt, both springs being arranged in mutual parallelism within the latch, and means, comprising a pair of independently operable vertically swinging arms each yieldingly held in inoperative position 130

by said second spring, to separably actuate said sliding member against both of said springs to retract said bolt.

7. A latch comprising a latching-bolt, a spring constantly forcing said bolt into its extended position, a unitary laterally sliding member bearing against said bolt only to retract same, a second spring connected with said unitary member to hold the latter under 10 outward spring pressure in all positions of

said latching-bolt, both springs being arranged in mutual parallelism, and means, comprising a pair of spaced-apart, independently operable vertically swinging arms each yieldingly held in inoperative position by 15 said second spring, to separably actuate said sliding member against both of said springs to retract said bolt.

NIXON LEE.
